(57) **CLAIM**

The ornamental design for a clutter-clearing robot, as shown and described.

DESCRIPTION

FIG. 1 illustrates a left, front, perspective view of a clutter-clearing robot showing the new design;

FIG. 2 illustrates a front elevational view thereof;

FIG. 3 illustrates a rear elevational view thereof;

FIG. 4 illustrates a right side elevational view thereof;

FIG. 5 illustrates a left side elevational view thereof;

FIG. 6 illustrates a top plan elevational view thereof;

FIG. 7 illustrates a bottom plan elevational view thereof;

FIG. 8 illustrates a front elevational view in an alternative configuration thereof;

FIG. 9 illustrates a left side elevational view in an alternative configuration thereof;

FIG. 10 illustrates a left, front, perspective view in an alternative configuration thereof;

FIG. 11 illustrates a left side elevational view in an alternative configuration thereof;

FIG. 12 illustrates a front elevational view in an alternative configuration thereof; and,

FIG. 13 illustrates a left, front, side perspective view of an alternative configuration thereof.

The broken lines shown are included for the purpose of illustrating portions of the clutter clearing robot only and form no part of the claimed design.
